(57) **CLAIM**

The ornamental design for a hot iron, as shown and described.

DESCRIPTION

FIG. 1 is a front perspective view of a hot iron in a closed orientation according to the invention;

FIG. 2 is a rear perspective view of the hot iron of FIG. 1 in an open orientation;

FIG. 3 is a top view of the hot iron of FIG. 1;

FIG. 4 is a bottom view of the hot iron of FIG. 1;

FIG. 5 is a right side view of the hot iron of FIG. 1;

FIG. 6 is a left side view of the hot iron of FIG. 1;

FIG. 7 is a front view of the hot iron of FIG. 1; and,

FIG. 8 is a rear view of the hot iron of FIG. 1.

The broken lines shown in the drawings illustrate portions of the article and form no part of the claimed design.
